UNITED STATES PATENT OFFICE.

EVERETT R. BURTNETT, OF LOS ANGELES, CALIFORNIA, ASSIGNOR, BY DIRECT AND MESNE ASSIGNMENTS, TO THE AUTOMOTIVE VALVES CO., OF LOS ANGELES, CALIFORNIA, A VOLUNTARY TRUST.

INTERNAL-COMBUSTION ENGINE.

Application filed June 18, 1925. Serial No. 37,991.

My invention relates to a multi-cylinder internal combustion engine that operates on the two stroke cycle principle, and the principal object of my invention is to provide a 5 twelve cylinder engine wherein the cylinders are arranged in two rows of six cylinders each, said rows being disposed so as to form a V-block, the wings of which are arranged 90° apart and in which a constant 10 reciprocatory mass inertia is developed at each crank pin so that complete rotary and reciprocating balance can be obtained by the use of a rotary counterweight part of the crank shaft that is equal to the total reciprocatory inertia weight developed at each 15 crank pin and the crank pin end arms.

I accomplish this result by providing a twin six engine with a three throw crank shaft and attaching four pistons to each crank 20 thereof. As a result of this arrangement, the two pistons at either end of both rows of six cylinders are connected to one of the three cranks of the crank shaft, the two pistons of the third and fourth cylinders 25 from either end of the two rows are connected to the second or center crank pin and the two pistons within the two cylinders at the remaining end of each row of cylinders are connected to the third or other end crank 30 pin of the crank shaft. As a result of this arrangement, the reciprocatory force can be canceled out in the plane in which it is developed, thus eliminating the development of reciprocating out-of-balance forces to be 35 countered from one plane to another and such result being possible due to the spacing of the two rows of six cylinders in the V-structure 90° apart.

The structure herein disclosed is an improvement upon the six cylinders in a row arrangement disclosed in my co-pending application now Patent No. 1,697,553, Jan. 1, 1929.

With the foregoing and other objects in view, my invention consists in certain novel 45 features of construction and arrangement of parts that will be hereinafter more fully described and claimed and illustrated in the accompanying drawing in which

Fig. 1 is a vertical section taken lengthwise 50 through the center of one of the wings of my improved engine.

Fig. 2 is a cross section taken approxi- 55 mately on the line 2—2 of Fig. 1.

Fig. 3 is a cross section taken approximately on the line 3—3 of Fig. 1.

55

Fig. 4 is a cross section taken approximately on the line 4—4 of Fig. 1.

Fig. 5 is a cross section taken approximately on the line 5—5 of Fig. 1.

Referring by numerals to the accompanying drawing which illustrates a practical embodiment of my invention, 10 and 11 designate cylinder blocks that occupy planes 90° apart and associated with the lower ends of said blocks is a crank case 12 having four 60 main bearings 13 for a crank shaft 14. This crank shaft has three crank throws and the pins 15, 16 and 17 of said three cranks are disposed 120° apart. Each crank pin has two finished bearing peripheries and ar- 65 ranged between each pair of peripheries and centrally upon each pin is an arm such as 18 that projects diametrically across the axis of crank shaft 14 and carried by the free end of each arm is a counterweight such as 19. 70

Each of the two wings of the V-block is provided with six cylinders the same being arranged to form three pairs and each pair comprises a bore or chamber of straight diameter and a bore or chamber having two 80 diameters.

As illustrated in Fig. 1, the pair of cylinders at one end of the wing includes a straight diameter bore combustion chamber 20 and a two diameter chamber that includes 85 a combustion chamber 21 and a pumping chamber 22. The chambers 21 and 22 are co-axial with the smaller chamber 21 arranged in the head or outer portion of the cylinder block. At the opposite end of the wing the pair of chambers includes a straight diameter bore combustion chamber 23 and co-axial chambers 24 and 25 of different diameters with the chamber of smaller diameter 24 disposed at the outer or head end of 90 the block.

Formed in the wing between the pairs of chambers just described is a straight diameter bore chamber 26 and co-axial chambers 100 27 and 28 of different diameters and with the chamber of smaller diameter 27 being disposed adjacent to the head or outer end of the block.

The axes of the three chambers 20, 26 and 23 and of the three co-axial chambers 21, 22, 105 27, 28 and 24, 25, are parallel and in the

same plane, and said axes intersect the axis of crank shaft 14. Thus the two sets of six cylinders each are arranged in two straight rows with the axes of the chambers in each 5 row parallel and with the axes of the twelve cylinders intersecting the axis of the crank shaft.

Secured on the head end of one wing is a head block such as 29 and formed in the 10 underside of each block are three shallow chambers 30, 31 and 32. Chamber 30 connects and functions as a common compression and combustion clearance space for the head ends of the combustion chambers 20 15 and 21 and in like manner chamber 31 connects and functions as a common compression and combustion clearance chamber for the head ends of combustion chambers 26 and 27. Chamber 32 connects and functions 20 as a common compression and combustion clearance chamber for combustion chambers 23 and 24.

Block 11 is fitted with a head block 29^a that is identical in construction with block 25 29 just described.

The pumping chambers 22, 25 and 28 in both blocks are provided at their upper ends with charge volume inlet ports such as 33 30 and with pumped charge volume outlet ports such as 34 from which lead suitably arranged transfer ducts 35. The combustion chambers 21, 24 and 27 in both blocks are provided 35 near their lower ends with charge volume inlet ports such as 36 and leading from the combustion chambers 20, 23 and 26 in both blocks are suitably located exhaust ports such as 37.

Located in the head blocks 29 and 29^a, preferably above the two-diameter chambers 40 21, 22, 27, 28 and 24, 25, are ignition devices such as spark plugs 38 and the terminals of the electrodes thereof project into the respective common clearance chambers 30, 31 and 32.

45 Arranged for reciprocatory movement within the straight diameter combustion chambers 20, 23 and 26 of both blocks are pistons such as 39, and arranged for reciprocatory movement within the two diameter chambers of both blocks are two-diameter pistons such as 40. The pistons within the pair of combustion chambers 20 and the adjacent pair of two-diameter chambers 21, 22, 50 in both wings of the V-block are connected to pin 15 of the crank shaft by suitable connecting rods 41 and thus the pistons within the four cylinders at one end of the engine are connected to the same crank pin.

In like manner the four pistons in the 60 straight diameter combustion chambers 23 and in the two-diameter chambers 24, 25, at the other end of the V-block are connected to crank pin 17 by connecting rods such as 42. The four pistons in the pair of straight 65 diameter combustion chambers 26 and the

pair of two-diameter chambers 27, 28, are connected to crank pin 16 by suitable connecting rods such as 43.

Thus it will be seen that I have provided an engine wherein the cylinder block is of 70 V-structure, the wings thereof being disposed 90° apart with each wing containing six cylinders that are arranged in three pairs and each pair comprising a chamber of straight diameter and a chamber of two 75 diameters.

A single crank shaft is provided having three crank pins arranged 120° apart and with four pistons, two from each wing, connected to each crank pin, and further that 80 each crank pin is counterbalanced by a weight carried at the free end of diametrically arranged arms. As a result of this arrangement a constant reciprocatory mass inertia is developed at each crank pin while 85 the engine is in operation and complete rotary and reciprocatory balance is obtained, thereby wholly eliminating the development of reciprocating out-of-balance forces and consequent vibration. 90

It will be understood that during operation of my improved engine a charge volume that is pumped from one of the pumping chambers enters the inlet port such as 36 95 to one of the combustion chambers of each two-diameter cylinder at the time that the piston therein is at low center and this charge volume in passing through the connected combustion chambers drives out through the corresponding exhaust ports 37 100 the greater portion of the burnt gases resulting from the previously ignited charge. As the pistons in the chambers into which the charge volume is admitted move upwardly 105 in their respective chambers the charge volume is compressed in the upper portions of said chambers and the clearance chamber connecting same, and as the pistons pass high center the compressed charge is ignited by a spark produced between the terminals 110 of the corresponding spark plug and the rise in pressure following combustion of the compressed charge acts directly upon the heads of the pistons to drive the same downward on their power stroke. 115

Inasmuch as the engine comprises six power units connected to the three crank pins of the crank shaft, the latter will receive six power impulses to each revolution and this will result in an even flow of power 120 during engine operation.

It will be understood that minor changes in the size, form and construction of the various parts of my improved engine may be made and substituted for those herein shown 125 and described without departing from the spirit of my invention, the scope of which is set forth in the appended claim.

I claim as my invention:

In a two stroke cycle internal combustion 130

engine, twelve cylinders arranged in two rows of six cylinders each, the six cylinders in each row being arranged in three pairs, each pair of cylinders comprising a cylinder having a straight diameter and a cylinder having a two diameter chamber, the larger portion of each two diameter chamber being provided on one side at its upper end with an inlet port and on the other side at its upper end with an outlet port, the smaller portion of each two diameter cylinder being provided near its lower end with an inlet port, the two rows of cylinders occupying angular planes ninety degrees apart, the six cylinders in one row being arranged in direct transverse alignment with the six cylinders in the other row, the heads of the members forming each pair of cylinders being connected by a common compression and combustion clearance chamber, a crank shaft 20 journaled for operation and arranged so that its axis is intersected by the axes of the twelve cylinders, said crank shaft having three crank pins spaced one hundred twenty degrees apart, pistons arranged for operation within the twelve cylinders, the lower ends of the pistons in the two diameter piston chambers being provided with enlarged portions that cover and close the inlet and outlet ports in the enlarged portions of the 25 two diameter chambers when the two diameter pistons are at the outer ends of their travel and connections from four of the pistons, two in each of the two rows of pistons, to each crank pin. 30 35

In testimony whereof I affix my signature.

EVERETT R. BURTNELL.
